UNITED STATES PATENT OFFICE.

WILLIAM CAMERON, OF TOLEDO, OHIO.

PIPE-WRENCH.

1,077,591.

Specification of Letters Patent.

Patented Nov. 4, 1913.

Application filed March 22, 1913. Serial No. 756,111.

To all whom it may concern:

Be it known that I, WILLIAM CAMERON, a citizen of the United States, and a resident of Toledo, in the county of Lucas and State 5 of Ohio, have invented a certain new and useful Pipe-Wrench; and I do hereby declare the following to be a full, clear, and exact description of the invention, such as will enable others skilled in the art to which 10 it appertains to make and use the same, reference being had to the accompanying drawings, and to the figures of reference marked thereon, which form a part of this specification.

15 My invention relates to wrenches of the class in which a strap is employed as a gripping element so that nickel-plated, brass or other highly-polished pipes can be gripped without danger of being marred by the 20 wrench.

The object of my invention is the provision of a wrench of this type, which is simple, strong and economical in its construction, composed of a few parts, and has 25 the strap engaging parts thereof so arranged that when in use such parts coöperate to securely hold the strap, and which eliminates the objectionable practice now commonly employed of sewing or riveting the strap to 30 one of such parts.

The operation, construction and arrangement of the parts of the invention are fully described in the following specification, and a preferred embodiment thereof is illustrated in the accompanying drawings, in 35 which,—

Figure 1 is a top plan view of the wrench in engagement with a pipe. Fig. 2 is a side view thereof with the forward end of the 40 wrench in longitudinal section, and Fig. 3 is a side view of the wrench with the jaws partly open.

Referring to the drawings, 1 designates the handle of the wrench, the forward end 45 of which is forked to provide two spaced longitudinally-extending arms 2, 2, the outer ends of which are connected by the integral cross-bar 3. Pivoted between the arms 2, 2, as at 4, is the movable jaw 5, which is provided near its free end with a transverse opening 6, and has such end extended in position to adapt it to coöperate with the cross-bar 3, as hereinafter described.

7 designates the strap or flexible pipe- 55 gripping element, one end of which is looped

through the opening 6 in the jaw 5 from the inner side thereof and securely held against withdrawal therefrom by a cam-bar 8, which is forced within such loop and opening and pivotally secured therein by a screw 9. The 60 major portion of the strap on leaving the opening 6 passes outwardly between the bar 3 and the free end of the jaw 5, thence around the pipe 10 on which it acts and back over the inner face of the bar 3, the surface 65 of which is corrugated to assist in preventing a slipping of the strap in contact therewith, and thence has its free end projected loosely between the arms 2, 2 of the handle.

When the wrench is placed in the position indicated in Fig. 2 relative to the pipe 10 to be turned and a turning stress is applied to the handle in the direction indicated by the arrow in such figure, the bar 3 acts as the fulcrum for the handle and strain on the 70 strap is applied mainly to the upper half of the loop which surrounds the pipe and has its end attached to the jaw 5. The jaw 5, however, is relieved very materially of the strain applied to the strap by reason of 75] the free end of such jaw being drawn toward the bar 3 whereby such jaw and bar coöperate to firmly grip the two thicknesses of the strap disposed therebetween, which gripping is augmented by resining the strap. 80]

It is apparent to persons familiar with the use of this class of tools that I have provided a smooth pipe wrench which is simple and efficient in its operation and construction, and which obviates the objections incident to the use of the wrenches of this class heretofore employed, in that it is stronger, has a more efficient gripping action, the strap is not liable to become disconnected from the jaw 5 due to strain, as is frequently 90] the case with straps that are secured to the metal parts by sewing or riveting and the jaw 5 is relieved from the strain to a considerable extent by the coöperating gripping action of the bar 3 and jaw 5. 95]

I wish it understood that my invention is not limited to any specific arrangement or construction of the parts except in so far as such limitations are specified in the claim.

Having thus described my invention, what 105 I claim as new and desire to secure by Letters Patent, is,—

A pipe-wrench comprising a handle having an end forked and the furcations thereof connected at their outer ends by a cross-bar 110

having a serrated surface, a jaw pivoted to said furcations and having a transverse opening, a strap having an end portion looped through the opening in said jaw and 5 a portion looped outwardly between said cross-bar and the free end of said jaw, said bar and jaw coöperating to firmly grip said outwardly looped portion of the strap when strain is applied thereto, and a rotatable 10 cam-bar removably secured within said

opening and coöperating with the jaw to attach the strap thereto.

In testimony whereof, I have hereunto signed my name to this specification in the presence of two subscribing witnesses.

WILLIAM CAMERON.
